Attorney

UNITED STATES PATENT OFFICE.

JOSEF TISSLER, OF PHILADELPHIA, PENNSYLVANIA.

RIVET HOLDER.

Application filed November 29, 1928. Serial No. 151,549.

The present invention relates to a rivet holder, and aims to provide an improved structure for holding a rivet in a riveting machine in such a manner that the holding means is released when the rivet spreading means comes into operation.

Another very important object of the invention lies in the provision of a movable rivet holder which will release the rivet when pushed by the spreading device a predetermined amount.

Another very important object of the invention lies in the provision of a rivet holder of this character which is simple in its construction, strong and durable, inexpensive to manufacture, not likely to easily become out of order, reliable and efficient, and otherwise well adapted for the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is a side elevation of the device embodying the features of my invention.

Figure 2 is a front sectional elevation thereof, and

Figure 3 is a top plan view of the rivet holder per se.

Referring to the drawing in detail it will be seen that the numeral 5 denotes a supporting structure of any suitable formation. A plunger 6 is mounted in the supporting structure 5 for vertical rectilinear movement, being operated in any suitable manner. The lower end of this plunger 6 is reduced as is shown in Figure 3 and this reduced end 7 has its lower end tapered as at 8, and the extremity is concaved as at 9. A skirt 10 is slidable over the reduced end 7 and has longitudinal slots 11 through which extends the pin 12 mounted in the reduced end 7, thus limiting the movement of the skirt in its relation to the end 7. A flange 14 is formed at the upper end of the skirt, and a spring 15 impinges thereagainst for normally holding the skirt extending downwardly beyond the lower extremity of the reduced end 7.

A horn 16 projects horizontally from the lower portion of the supporting structure 5, and the upper face thereof is provided

with the recess 17 having in the bottom thereof a downwardly extending pocket 18 formed with an intermediately disposed shoulder 19. A head 20 is formed with a depending shank 21 vertically movable in the pocket 18. A cross member 22 is threadedly engaged on the threaded portion 23 of the intermediate portion of the shank 21 adjacent the head 20. A spring 24 impinges against the shoulder 19 and against the cross member 22 normally holding the head 20 in a raised position. A cross bar 25 is provided at the base of the head 20 and has upwardly projections 26 with slots 27 therein. Links 28 are pivoted on the extremities of the cross member 22 and are pivoted to intermediate portions of fingers 29 which project through the slots 27 and then extend upwardly and then inwardly over the top of the head 20. The other ends of these fingers are directed downwardly and have pins 30 projecting into arcuate slots 31 provided in the side walls of the recess 17. The lower edges of these arcuate slots 31 function as cams. Suitable buffing material 33 is disposed in the bottom of the pocket 18.

When the parts are disposed as in Figure 1, it will be seen that a rivet may be rested on the head 20 and held in place by the fingers 29. When the plunger 6 is forced downwardly, the lower edge of the skirt 10 will first engage with the material and be disposed about the upward projecting end of the rivet, thus guiding the reduced end 7 into engagement with the rivet in proper relation for spreading the extremity of the rivet. As the plunger proceeds downwardly and engages the rivet the head 20 will be forced downwardly, thus contracting the spring 24 and at the same time causing the cross member 22 to pull downwardly on the links 28 thereby pulling downwardly on the fingers 27 and the downwardly and outwardly curved cam slots 31, therefore, will cause the pins 30 to move to the lower ends thereof, thus causing the releasing positions of the fingers 29 to occur, at which time the shank 21 will have engaged the proper material 33 and stopped so that the end of the rivet is flattened or spread as desirable.

It is thought that the construction, operation and advantages of this invention will now be apparent to those skilled in this art without a more detailed description thereof. The present embodiment of the invention has been disclosed in detail merely by way of

example since in actual practice it attains the features of advantage enumerated as desirable in the statement of the invention and the above description. It will be apparent that changes in the details of construction, and in the combination and arrangement of parts may be resorted to without departing from the spirit and scope of the invention as hereinafter claimed without sacrificing any of its advantages.

Having thus described the invention, what I claim as new and desire to secure by Letters Patent is:—

1. A device of the class described, including a supporting structure having a recess and a pocket in the recess, a shank movable in the pocket, a head on the shank in the recess, a cross member adjustable on the shank, links pivoted to the cross member, fingers pivoted intermediate their ends to the links, the side walls of the recess being provided with slots, said fingers having pins extending into the slots, a spring means normally urging the shank upwardly and

the fingers in a position to engage the rivet 25 on the top of the head, said slots being curved to direct the fingers away from the head when the head is moved downwardly.

2. A device of the class described, including a supporting structure having a recess and a pocket in the recess, a shank movable in the pocket, a head on the shank in the recess, a cross member adjustable on the shank, links pivoted to the cross member, fingers pivoted intermediate their ends to 30 the links, the side walls of the recess being provided with slots, said fingers having pins 35 extending into the slots, a spring means normally urging the shank upwardly and the fingers in a position to engage the rivet on the top of the head, said slots being curved 40 to direct the fingers away from the head when the head is moved downwardly, and rivet spreading means for pushing said head 45 downwardly.

In testimony whereof I affix my signature.

JOSEF TISSLER.
